UNITED STATES PATENT OFFICE.

CHARLES NAPIER, OF SPRINGFIELD, MASSACHUSETTS, ASSIGNOR OF
ONE-HALF TO EDWARD S. BRADFORD, JR., OF SPRINGFIELD, MAS-
SACHUSETTS.

SAW-SETTING MACHINE.

No. 817,440.

Specification of Letters Patent.

Patented April 10, 1906.

Application filed September 3, 1904. Serial No. 223,218.

To all whom it may concern:

Be it known that I, CHARLES NAPIER, a citizen of the United States of America, residing at Springfield, in the county of Hampden and State of Massachusetts, have invented new and useful Improvements in Saw-Setting Machines, of which the following is a specification.

This invention relates to saw-setting machines, the object thereof being to provide a machine of this character through which saws may be fed continuously between suitable guides, the teeth of the saw passing between the ends of intermeshing toothed wheels, whereby the teeth are successively set out of line with the plane of the blade as desired.

The invention is fully illustrated in the accompanying drawings, in which—

20 Figure 1 is a plan view of the machine in which is embodied this invention in its preferred form. Fig. 2 is a sectional elevation of the same on line 2 2, Fig. 1. Fig. 3 is a side elevation of the machine viewed from 25 the right-hand side of Figs. 1 and 2. Fig. 4 is an enlarged sectional plan view of a portion of the intermeshing setting-wheels, showing the relation of the teeth thereof to the saw. Fig. 5 is a sectional elevation of 30 that part of the setting-wheels shown in Fig. 4, said section being on line 5 5 of that figure. Fig. 6 is a perspective view of a saw-guide. Fig. 7 is a cross-section of the saw, whose teeth are set according to the invention described herein.

35 Referring to the drawings, the mechanism is supported on a suitable bed *a*, provided with legs *b*. Beneath the bed in a hanger *c* is a short driving-shaft *d*, provided with the 40 usual driving-pulley *e*. On the driving-shaft *d* is the worm *f*, which meshes with the worm-gear *g*, fixed on a vertical shaft *h*, which is supported in a bearing *j* on the bed of the machine. Secured on said shaft below the 45 worm-gear *g* is the gear *k*, which in turn meshes with a like gear *m* on a vertically-disposed shaft *o*, supported in parallelism with the shaft *h* and in a similar bearing. These shafts *h* and *o* extend above the bed *a*, their 50 upper ends being supported by a bracket *p*, bolted to the bed and having bearings for the ends of the shafts. On these shafts between these bearings and the surface of the bed-plate the intermeshing saw-setting disks are

located, these being revoluble with the 55 shafts, said disks being indicated, respectively, by *r* and *s*, and they are located on their respective shafts at some little distance above the surface of the bed, as shown in Figs. 2 and 3, whereby space is provided for a 60 saw-guide *t*, which extends from one side of the bed to the other and is loosely secured on one side of the machine, as by a bolt *a'* or other suitable means, which will permit the free end of the guide to move more or less in a 65 vertical plane. The center line of the guide is located in the same vertical plane as the points of intersection of the teeth on the two setting-disks *r* and *s*, and it extends across the bed of the machine and beyond the edge 70 of the latter in such position that its overhanging end may be engaged by a lever *a''*, pivotally supported on the machine and provided with a weight *a'''* whereby a saw in the guide *t* may have its teeth always yieldingly 75 pressed into the inverted-V-shaped space formed by the intersection of the oblique lower ends of the intermeshing teeth on the setting-disks, as will be described farther on.

The saw-guide *t* is shown in perspective on 80 a somewhat-reduced scale in Fig. 6 and consists of a metal bar having downhanging ends through which screws pass which secure the guide to the bed-plate. On the upper side of the guide are two raised ribs *t'*, having a longitudinally-disposed slot *t''* between them, into the end of which saws may be introduced one after the other by the operator, the teeth of the saws being uppermost. Toward the forward end of the ribs *t'* the upper edge 90 thereof is milled off, as shown in Fig. 6, to expose the teeth of the saw, and at this point the teeth are engaged by a rotary feeding-wheel *u*, the relation thereof to the saw being clearly shown in Fig. 2. The extreme forward edges of the ribs *t'* are beveled off in a vertical plane to permit them to be introduced between the setting-disks *r* and *s* close up to the point of their intersection, whereby the saw may be steadied and rigidly supported in a vertical plane. The feeding-wheel *u* is 95 constructed with teeth on its periphery adapted to engage the teeth of the saw, and this wheel is supported on a short shaft *v* in a bearing *w* on the bed. This wheel *u* is rotated by means of the beveled gears *x* and *y*, the former being fixed on the shaft *v* and the latter on a vertically-disposed shaft *z*, sup-

ported in a bearing on the bed-plate parallel with the shafts *o* and *h* and receiving movement from the shaft *o* through a gear 4 on its lower extremity which engages with the gear 5 *m* on the shaft *o*. The teeth 5 on the disks *r* and *s* are spaced to correspond to the spacing between the teeth of the saws on which they are to operate, and preferably these teeth do not touch each other at any point, the gears 10 *m* and *k* being cut so accurately that this contact, which is needless, may be prevented. By referring to Figs. 4 and 5 the peculiar formation of the teeth 5 and the relation thereto to the teeth of the saw, as well as the general 15 relation of the disks to the saw, will be clearly apparent. The diameter of that portion of the disks *r* and *s* on which the teeth 5 are cut is somewhat greater than the diameter of the portion below the teeth, whereby provision is 20 made for the intermeshing of these teeth (which extend only through said enlarged portion of the disks) without bringing the lower edges of the latter together, whereby a passage between the disks is left for the saw 25 7, the teeth of which extend beyond the intersecting line of the teeth on the disks.

It will be seen that the lower ends of the teeth 5 of the setting - disks are inwardly curved, as at 8, Fig. 5, which curve represents 30 substantially the degree of the "set" it is desired to give to the teeth and represents substantially the outward curve of the tooth. It will be noticed that the bottom of the cut between two of the teeth 5 extends inward beyond the plane of the periphery of these disks, between which the saw 7 is guided, thereby forming pockets to receive the teeth of the saw as they are forced to the right and left by the passage of the saw between the 35 disks.

From the foregoing description it will be clear that the operative portion of the teeth 5 is the lower end thereof only and that part thereof above said lower ends, except such as 40 is needed for strength, may be done away with, provided the driving of the disk is not dependent upon their mutual engagement. The teeth 5 are made as shown herein to permit of grinding off their operative edges as 45 they wear away. This wear, however, is very small, as the surfaces of the teeth are relatively broad, and the disks may be hardened.

As to the manner of feeding the saw to the 55 setting-disks, the particular feeding devices herein shown are not essential to the successful operation of the machine, for any feeding device whereby the teeth of the saw when introduced between the disks would be located 60 in proper relation to the teeth 5 of those disks might be used instead of the devices shown herein without departing from the invention—that is to say, the feeding devices must be in "time" with the disks, and this is 65 provided for by the system of gearing herein-

before described, and the teeth of the saws should be yieldingly pressed up into engagement with the ends of the teeth 5 on the setting-disks. It is obvious that once engaged between the disks the saw will feed itself— 70 that is to say, it will be drawn through between the rotating disks by the engagement between the teeth of the saw and the lower ends of the teeth 5, the saw-teeth being bent over between the teeth 5 as it moves on between the disks. 75

Preferably the machine is built with the disks *r* and *s* non-adjustable. It might be desirable, however, to effect slight adjustments of the disks one toward the other, 80 whereby the degree of "set" of the saw-teeth may be changed more or less. One method whereby this adjustment could be effected would be, for example, to divide the bracket *p*, as shown at 10, Fig. 3, making one-half of 85 it—say the right-hand end—adjustable toward the other half, the two parts being secured together by a screw 10^a, then making the bearing *j* of this shaft adjustable in the bed-plate in a slot therein and securing the 90 bearing, as by an arm 12, to the movable half of the bracket-arm *p*, whereby the entire shaft *h* and its bearings could be moved more or less toward or away from the shaft *o*. Of course the extreme limit of this adjustment 95 would be very small.

The formation of a saw-tooth on a curved line, as shown in Fig. 7, instead of on an oblique straight line (which is the present practice) is of very great importance, as it presents a rounded cutting-surface to the material which it is operating on and will cut much faster for the same reason that a round-nosed chisel will cut faster than a flat chisel. This undoubtedly is due to the fact that the 105 curved cutting-tooth breaks away the chip which forms in front of it immediately, whereas a flat chip will hang together longer, and thus constitute more of a shoulder against which the teeth of the saw must be 110 pushed. Whatever the explanation may be, it is a fact capable of demonstration in practice that a saw, especially a hack-saw, such as is used on metals having teeth set on a curve such as is formed by means of the machine described herein will cut more than one-third faster than a saw set in the usual manner. 115

It will sometimes happen that the blanks are narrower at one end than the other, and when these blanks are toothed and put through the setting-machine the teeth on the narrower end thereof would not extend up into the intermeshing teeth of the second disks if the saw-guide were immovable; but 120 with the latter pressed yieldingly upward a saw passing therethrough will have the teeth thereon forced upward against the ends of the teeth of the setting-disk in such manner that the narrower end of the blade will have 125 130

its teeth set in the same manner as though the blade were of full width.

From the foregoing it is to be understood that the essential features of the invention 5 reside in the combinations which include the setting members *r s* and the elements 5 5, 8 8, 7, and *t*. This construction provides for properly and rigidly holding the saw within 10 the plane where the thrust occurs for setting the teeth. Also the extended length of the teeth 5 permits of regrinding, and the yielding abutment and guide *t* serve to support and thrust the saw against the setting-bevels.

Having thus described my invention, what 15 I claim, and desire to secure by Letters Patent of the United States, is—

1. In a saw-setting machine, a pair of rotatable setting members provided with plain saw-holding disk portions, and toothed portions, the toothed portions of said members having an intermeshing relation and provided at their inner ends with setting-bevels deflected toward and leading to said plain or untoothed portions, and a guide and abutment located at one side of the untoothed portions of said members and arranged to support the saw against the setting-bevels. 25

2. In a saw-setting machine, a pair of rotatable setting members provided with plain saw-holding portions, and with toothed portions, the toothed portions of said members having an intermeshing relation and provided at their inner ends next to the untoothed portions with setting-bevels, and a yielding guide and abutment located at one 30 side of the untoothed portions of said members, and arranged to support the saw against the setting-bevels. 35

3. In a saw-setting machine, a pair of rotatable disks provided with plain saw-holding portions of one diameter and intermeshing toothed portions of a larger diameter than said plain portions, and intermeshing teeth extending entirely across the portions of greater diameter and provided at their inner ends with setting-bevels, and a yielding guide and abutment arranged to yieldingly hold the saw through the space between the untoothed portions of the disks and against the setting-bevels. 40 45

CHARLES NAPIER.
